UNITED STATES PATENT OFFICE.

BENJAMIN HELLER, OF CHICAGO, ILLINOIS.

CAN-CLOSURE.

1,156,777.

Specification of Letters Patent.

Patented Oct. 12, 1915.

Application filed May 27, 1914. Serial No. 841,377.

To all whom it may concern:

Be it known that I, BENJAMIN HELLER, a citizen of the United States, residing at Chicago, in the county of Cook and State 5 of Illinois, have invented certain new and useful Improvements in Can-Closures; and I do hereby declare the following to be a full, clear, and exact description of the invention, such as will enable others skilled in 10 the art to which it appertains to make and use the same.

This invention relates to can closures embodying multiple covers and has for an object to provide a closure with new and im- 15 proved features of convenience and security.

A further object of the invention is to provide a closure wherein the tendency of the internal friction cover to distend the neck of the can is resisted by the flange of an ex- 20 ternal slip cover.

With these and other objects in view the invention comprises certain novel constructions, combinations and arrangement of parts as will be hereinafter more fully de- 25 scribed and claimed.

In the drawings: Figure 1 is a view of the top of a can in perspective. Fig. 2 is a sectional view of the top of a can with the closures in position. Fig. 3 is a sectional 30 view of the top of a can with the friction cover removed and the slip cover in position.

Like characters of reference designate corresponding parts throughout the several views.

The improved can closure which forms the subject matter of this application contemplates the use of any approved form of can body whose top is flat or conical and whose mouth comprises a cylindrical neck 35 having around its upper edge a flange 12 turned inwardly and then downwardly. Within the inwardly and downwardly turned flange 12, a friction cover 13 is employed substantially like the ordinary friction cover except that it has its edge up- 40 turned and then carried horizontally outwardly into an annular flange 14 adapted to rest upon the upper surface of the flange 12. As usual this friction cover is driven into 45 the downturned flange and held therein with some considerable friction which necessarily 50 slightly distends the neck 10.

The exterior of the neck is substantially cylindrical and a slip cover 15 is provided having a downturned cylindrical skirt 16 55 which incloses the cylindrical portion of the neck 10 and is of a height corresponding therewith, as shown more particularly at Figs. 2 and 3.

When a can is filled with a substance 60 which deteriorates by exposure to the atmosphere it is packed with the friction cover 13 in position which friction cover as is well known is substantially air tight. The slip cover 15 is then put in position as shown in 65 Fig. 2, and its skirt by inclosing and gripping the exterior of the neck 10 serves to retain the tapered friction cover 13 in position. When the can is received by the consumer the slip cover is removed, the friction 70 cover is next removed by inserting any desired instrument under the flange 14 and prying it off and the slip cover 15 then put back in position for retaining the contents of the can in condition while being used. 75

It will be found that, while the slip cover fitted rather tightly when the friction cover was in place, now that the friction cover is removed the slip cover slides over the cylindrical neck rather easily and drops a little 80 farther thereon as seen in Fig. 3, so that the lower edge of its skirt incloses the lower end of the neck where the latter merges into the body, rather than a little higher up as seen in Fig. 2.

As the period of use is short compared to the period of storage and shipment, it is not necessary that the sealing of the can be absolutely complete while being used, as it is while being shipped and stored. 85

Friction covers are difficult to remove and replace and ordinarily are but indifferently replaced; consequently the contents of the can deteriorates rapidly after being opened.

With my improved combined closure, the 90 friction cover may be removed and discarded, the slip cover retaining the material in the desired condition during the period of use.

I claim:

The combination with a metal can hav- 100 ing a cylindrical neck provided at its upper end with a flat inturned flange bent downwardly at its inner edge; of a friction cover whose body lies in a plane below said flange

and whose edge is turned upward and fits closely within the downturned portion of the flange with a wedging action, said edge having an outturned flange overlying that of the neck; and a slip cover including a flat body spaced from that of the friction cover and extending over said outturned flange, and a cylindrical skirt depending

from the periphery of its flat body and frictionally inclosing said neck.

10

In testimony whereof I affix my signature in presence of two witnesses.

BENJAMIN HELLER.
